UNITED STATES PATENT OFFICE.

JOHN B. OWENS, OF ZANESVILLE, AND ELLSWORTH P. OGDEN, OF COLUMBUS, OHIO;
SAID OGDEN ASSIGNOR TO SAID OWENS.

COMBUSTION-CHAMBER FOR TUNNEL-KILNS.

1,378,190.

Specification of Letters Patent.

Patented May 17, 1921.

Original application filed May 28, 1918, Serial No. 237,166. Divided and this application filed June 25, 1920. Serial No. 391,637.

To all whom it may concern:

Be it known that we, JOHN B. OWENS and ELLSWORTH P. OGDEN, citizens of the United States, residing, respectively, at Zanesville, county of Muskingum, State of Ohio, and Columbus, in the county of Franklin and State of Ohio, have invented certain new and useful Improvements in Combustion-Chambers for Tunnel-Kilns, of which the following is a specification.

In earlier applications of John B. Owens, instances of which are Serial Nos. 144,071; 237,166; 249,827; 251,294 and 277,718, there are disclosed and claimed the principles of longitudinal firing in combustion chambers for tunnel kilns and baffles which deflect the heat and products of combustion from the combustion chambers into the tunnel. The objects have been, generally stated, to evolve a maximum number of thermal units in the combustion chambers and to so discharge the thermal units and products of combustion onto the ware or goods being burned in the tunnel as to minimize uneven burning and to insure an even firing of the ware at different points of the height of the stack of ware carried by the cars or other conveyors which convey the ware through the tunnel.

Our present improvements relate to combustion chambers for tunnel kilns and, more particularly, to baffles or walls for said combustion chambers for the purpose of directing the thermal units and products of combustion to the ware on the cars in such manner that an even firing of the ware will be had; further, to so construct the inner walls or faces of the combustion chambers opposite the tunnel as to guard against any of the ware falling into the combustion chambers should the intense heat, despite the improvements, result in uneven firing of the ware and cause the latter to sag and fall laterally when opposite the combustion chambers.

Heretofore, despite all precautions, such accidents have happened, resulting in congestion of the kiln and the combustion chambers and requiring a shut-down.

Our present improvements overcome the defects in question and provide what is, in effect, relatively closed faces for the combustion chambers where they face the tunnel and yet full provision is made for passage of the thermal units and products of com-

bustion through the baffles in such manner that an even firing of the ware is obtained.

In application Serial No. 237,166 it is explained that the depending baffles for the combustion chambers may be provided with perforations and built as checker work. In that application is also shown piers supporting the depending baffle wall and dividing the space below the lower edge thereof into ports or openings, whose number may be varied as desired, through which the heat and products of combustion flow to the ware in the tunnel.

The present application is, therefore, as to the above features broadly considered, a division of application Serial No. 237,166, filed May 28, 1918, and we have disclosed herein certain additional and improved features constituting novel subject-matter.

In the accompanying drawings,

Figure 1 is a horizontal section on line 1—1 of Fig. 2 taken through one part of the combustion chambers of a tunnel kiln according to the present invention;

Fig. 2, a vertical section on line 2—2 of Fig. 1, and

Fig. 3, a view looking toward the inner face of the combustion chamber which opens into the interior of the tunnel, the tunnel appearing in longitudinal section.

We have illustrated only one pair of oppositely disposed combustion chambers but it is to be understood that our invention may be carried out in connection with any number of pairs of combustion chambers as, for instance, it may be used in connection with the combustion chambers of a tunnel kiln having a multiple firing zone using two, three, four or greater number of pairs of combustion chambers.

A portion of the tunnel of the kiln appears at 1 and a pair of oppositely disposed combustion chambers are shown at 2, 2. These chambers may be fired in any desired manner and by the use of any preferred fuel, but we have shown openings at 3 and 4, respectively, in the ends of the chambers for the introduction of fuel and air which will be directed longitudinally of the combustion chambers to carry out the principle of longitudinal firing which is fully explained in earlier applications, the serial numbers of some of which are hereinbefore recited. The chambers may be fired longitudinally from both ends if desired.

The rails are shown at 5 and one of the cars bearing ware appears at 6, the ware being illustrated at 7.

The car platform is substantially level 5 with the bottoms 8 of the combustion chambers.

The baffles are shown at 9, said baffles depending from the single large arch 10 which forms the crown of the tunnel and the side 10 walls of the combustion chambers, said arch having the attributes set forth in earlier applications. The baffles 9 are supported by piers 11 of which there may be as many as desired, say five or six, and of any desired 15 height. We do not limit ourselves to the vertical height of the baffles 9 nor to the height of the piers 11, nor to their number, nor to the size, and precise direction of delivery through, the openings or ports 12 20 between the piers.

A baffle supported by piers with ports between the piers for delivering the heat and products of combustion from the combustion chambers into the tunnel, is shown 25 and described in application Serial No. 237,166, filed May 28, 1918. That application also describes a baffle, such as shown at 30 9, which is provided with perforations for the passage of the heat and products of combustion therethrough, and it is stated in said application that the baffle may be built of checker work. In so far as there is shown and disclosed herein a baffle 9, piers 11 and ports 12 which are similar in general arrangement and function to the disclosures 35 of application Serial No. 237,166, we claim said subject-matter to constitute a division of said application Serial No. 237,166.

In addition to the foregoing features, we 40 provide in the face of the baffle 9 where it faces the interior of the tunnel, ports 13. These ports receive the heat and products of combustion from the upper part of the combustion chamber through a single long flue 45 14 which opens into the upper part of the combustion chamber at 15. The flue 15 may be of any width considered vertically, and it also extends the full length of the combustion chamber. The exact point where 50 the mouth 15 opens into the combustion chamber is not of the essence of the invention. Nor is it essential to our invention as to how the baffle 9 is formed for the purpose of providing the flue 14, mouth 15, and discharge ports 13.

Our improvements provide for the baffling and retardation of the heat and products of combustion and insure that they be directed toward the middle and lower portions of the 55 stack of ware 7. The heat and products of combustion thus are disseminated upwardly throughout the stack of ware 7 instead of being concentrated on the upper portion of the ware as would be the case were the baffle not used. The provision of the ports 12 and

13 insures that the heat and products of combustion be subdivided into numerous streams which tend to cause even firing instead of the heat being concentrated on certain points of the stack 7.

70

In our invention it is immaterial whether the ports 12 and 13 are arranged to direct the heat and products of combustion substantially at right angles to the length of the tunnel or are arranged on an incline to 75 direct the heat and products of combustion angularly to the length of the tunnel.

75

Our improvements provide, in substance, a wall for the inner face of the combustion chamber and, consequently, should the heat 80 cause the stack of ware to sag or cave in, due to concentration of heat on a particular part of the stack, the ware will simply brush against the baffle and the piers and not fall into the combustion chamber, thereby 85 overcoming a serious defect heretofore existing in tunnel kilns.

85

What we claim is:

1. A tunnel kiln having a combustion chamber at its side, a baffle for the upper part 90 of the combustion chamber where the latter faces the interior of the tunnel, and piers supporting said baffle, said piers being separated by discharge ports or passages through which the heat and products of combustion 95 pass from the combustion chamber to the interior of the tunnel, said baffle being provided with ports which open into the interior of the tunnel at the lower portion of said baffle and communicate with the combustion chamber in the upper portion thereof.

100

2. A tunnel kiln having a combustion chamber at its side, and a baffle depending from the upper portion of the combustion 105 chamber where it faces the interior of the tunnel, said baffle being provided with ports which communicate with the tunnel at the lower portion of the baffle and communicate with the combustion chamber at the upper 110 portion of the latter.

105

3. A tunnel kiln having combustion chambers at its sides, an arch constituting the crown of the tunnel and the walls of said combustion chambers, baffles depending from 115 said arch for said combustion chambers, said combustion chambers being in communication with the interior of the tunnel through a plurality of diving passages, ports or openings in the baffles which are arranged to deliver the heat and products of combustion from the upper parts of the combustion chambers to the middle and lower portions of the stacks of ware being conveyed through the tunnel.

115

In testimony whereof we affix our signatures.
